UNITED STATES PATENT OFFICE

GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

FLUID PRESSURE TOOL

Application filed August 17, 1929. Serial No. 386,523.

This invention relates to fluid pressure drills of the percussive type and more particularly to forms of the same which provide for blowing the cuttings out of the drill hole during the drilling operation. In certain aspects it may be considered as an improvement upon, or further development of, the invention disclosed in my copending application Serial No. 314,893, filed October 25, 1928.

One object of the invention is to provide fluid pressure means under manual control to maintain the moving parts of the tool in positions such as to pass pressure fluid to the bottom of the drill hole. Other objects will be apparent from the detailed description which follows.

In order to illustrate the invention one concrete embodiment thereof is shown in the accompanying drawings in which:

Fig. 1 is a top plan view;

Fig. 2 is a sectional view substantially on the line 2—2 of Fig. 1 but showing the drill steel in elevation;

Fig. 3 is an end elevational view of the cylinder of the tool after the back head has been removed;

Figs. 4 and 5 are fragmentary sectional views on the line 4—4 of Fig. 3, showing the manual control valve in different positions; and

Fig. 6 is a fragmentary sectional view substantially on the line 6—6 of Fig. 3.

The embodiment of the invention, chosen for the purpose of illustration, comprises a fluid pressure percussive tool or rock drill, generally conventional in form, having a cylinder 7 providing a piston chamber 8 within which reciprocates a hammer piston 9 having an extension 9a adapted to deliver blows to a hollow drill steel 10 supported in the front head 11 of the drill. Piston 9 carries at its rearward end a rifle nut 12 which cooperates with a rifle bar 13 having bearings in cylinder ring 14 and back head 15 and with the

usual ratchet arrangement in the back head. The rotation imparted to piston 9 by the rotation mechanism, is transmitted by splines or ribs 9c on piston extension 9a to chuck 16 which receives the polygonal shank of drill steel 10. The grooves between ribs 9c permit the passage of motive fluid from the forward end of piston chamber 8 to the bore 10a of the drill steel to blow out the cuttings when the piston is in its rearward position. 50 A water tube 17 of conventional form, mounted in back head 15 and extending through axial bores in rifle bar 13 and piston 9, may feed water into bore 10a of the drill steel to assist in washing out the cuttings and to eliminate dust. The cylinder is provided with a main exhaust chamber 18 substantially centrally thereof and controlled by the head of piston 9 on its reciprocations. 55

An automatically thrown valve 19, which is of the same general form as that disclosed in my aforesaid copending application, distributes the pressure fluid, admitted by throttle valve 20 actuated by handle 21, to the opposite ends of the piston chamber. Valve 19 is tubular in form with end areas of differential extent continuously subjected to motive fluid, the larger end area being remote from the fluid inlet. A shoulder 22 is subjected to air trapped and compressed by piston 9 on its rearward stroke for moving the valve forwardly, and such compressed air may be augmented, if desired, by live motive fluid in limited amount escaping through a small port 23 in the valve itself. 60 To throw the valve in the rearward direction, the same is provided with an annular flange 24, one face of which is continuously vented to atmosphere through a port 25, the opposite face 24a of greater extent than the 65 combined areas of shoulder 22 and the adjacent or smaller end area being intermittently supplied with motive fluid from the piston chamber by a passage 26 controlled by the piston. A vent passage 27 of smaller 70

60

65

70

75

80

85

90

capacity than supply passage 26 is provided for relieving the pressure on area 24a. A vent passage 28 also leads from the rear end of the piston chamber 8. The purpose of 5 these last named vent passages and the manner of controlling the same will presently be described.

To permit blowing out the drill hole as desired, a manually operated valve of any 10 suitable or desired type is provided for controlling main exhaust 18 as well as vent passages 27 and 28. The valve 29 herein shown (Figs. 1 and 3-6) is of the Corliss or cylindrical type which is supported for rotation or oscillation in a projection 7a on the cylinder casing the bore of which may be lined, if desired, by a bushing 30. A spring handle 31 straddles projections 7a to retain valve 29 in place, and to provide manual 15 means for oscillating the same, suitable sockets, such as 32, receiving the sides of handle 31 yieldingly to maintain the same in adjusted position. For normal drilling operation handle 31 is disposed in the position indicated 20 in Figs. 1, 4, and 6 wherein an arcuate recess 29a (Fig. 4) in the valve establishes communication between the main exhaust groove 18 for the piston chamber and an exhaust port 33 in the cylinder casing. In this 25 position a bore 29b through valve 29 in spaced relation to recess 29a also establishes communication between the restricted venting passage 27 for valve shift area 24a (Figs. 2, 3, and 6) and an exhaust port 34.

30 When it is desired to blow the cuttings out of the drill hole, handle 31 of manual exhaust valve 29 is pulled back until its sides snap into sockets 32, the valve being then in the position shown in Fig. 5 where both main 35 exhaust 18 and valve vent 27 are closed. Vent passage 28 leading to the rear end of the piston chamber is then put in communication with exhaust port 33 by the arcuate recess 29a in the valve. Pressure will then 40 be maintained against rearward valve shift area 24a since it cannot escape through passage 27, and valve 19 will be maintained in the position shown in Fig. 2. If desired, a small live air port 35 may be provided in the 45 valve (Fig. 2) to replace any leakage and positively to prevent forward movement of the valve. Since live air continuously passes to the forward end of the piston chamber, the piston will be held in its rearward position 50 (not shown), thus exposing the grooves in piston extension 9a and permitting the live air to pass down the bore 10a of the drill steel to blow the cuttings out of the drill 55 hole. Pressure cannot develop against shift shoulder 22 of valve 19 since all pressures in the rear end of the piston chamber including that admitted through port 23 in the valve 60 passes to atmosphere through vent passage 28. On throwing exhaust valve handle 31

to the forward position, (Fig. 1) the tool will resume its normal drilling operation.

While the invention has been herein disclosed in what is now considered to be a preferred form, it is to be understood that the 70 invention is not limited to the specific details thereof but covers all changes, modifications, and adaptations within the scope of the appended claims.

I claim as my invention:

1. In a fluid pressure percussive tool, a cylinder providing a piston chamber, a piston reciprocable therein and provided with an extension having grooves, means for supporting a hollow drill steel to receive the blows of 80 said piston, an automatically thrown valve for controlling the distribution of motive fluid for actuating said piston, said cylinder having an atmospheric exhaust port for said piston chamber under control of said piston, 85 and means including a normally open vent for one of the pressure areas of said valve and manually operated means for simultaneously opening and closing both said vent and said exhaust port, thereby at will to dispose 90 said piston in position to permit pressure fluid to pass along the grooves thereof to the hollow drill steel.

2. In a fluid pressure percussive tool, a cylinder providing a piston chamber, a piston 95 reciprocable therein and provided with an extension having grooves, means for supporting a hollow drill steel to receive the blows of 100 said piston, an automatically thrown valve for controlling the distribution of motive fluid for actuating said piston, and means including a normally open vent for one of the pressure areas of said valve and a normally closed vent for the rear end of said 105 piston chamber, and manually operated means for controlling said vents.

3. In a fluid pressure percussive tool, a cylinder providing a piston chamber, a piston reciprocable therein and provided with an extension having grooves, means for supporting a hollow drill steel to receive the 110 blows of 115 said piston, an automatically thrown valve for controlling the distribution of motive fluid for actuating said piston, said cylinder providing a vent for a pressure area of said valve and a vent for the rear end of said piston chamber and a main exhaust port controlled by said piston, and a single manually operated valve for controlling said 120 vents and said exhaust port.

4. In a fluid pressure percussive tool, a cylinder providing a piston chamber, a piston reciprocable therein and provided with an extension having grooves, means for supporting a hollow drill steel to receive the 125 blows of 130 said piston, an automatically thrown valve for controlling the distribution of motive fluid for actuating said piston, said cylinder providing a vent for a pressure area of said valve and a vent for the rear end

- of said piston chamber and a main exhaust port controlled by said piston, and a single manually operated valve for controlling said vents and said exhaust port, said last named 5 valve in one position establishing connection of said valve vent and of said main exhaust with atmosphere and in another position cutting off the same and connecting said piston chamber vent to atmosphere.
- 10 5. In a fluid pressure percussive motor in combination, a cylinder providing a piston chamber, a piston reciprocable therein, and an automatically thrown valve for controlling the distribution of motive fluid for actuating said piston, said valve being tubular and arranged to receive the motive fluid therewithin and to control its access to said piston chamber by the ends thereof, said ends of said valve presenting differential end 15 areas, said valve having an additional pressure area adjacent the smaller of said differential areas and always in communication with one end of the piston chamber so as to be subject to air compressed by the piston at 20 one end of its stroke thereby to assist the pressure of the live motive fluid upon the smaller of said differential end areas to overcome the pressure on the opposed larger differential area thereby to shift the valve, and 25 manually controlled venting means for said end of said piston chamber.
- 30 6. In a fluid pressure percussive motor in combination, a cylinder providing a piston chamber, a piston reciprocable therein, and an automatically thrown valve for controlling the distribution of motive fluid for actuating said piston, said valve being tubular and arranged to receive the motive fluid therewithin and to control its access to said 35 piston chamber by the ends thereof, said ends of said valve presenting differential end areas, said valve having an additional pressure area adjacent the smaller of said differential areas and always in communication with one end of the piston chamber so as to be subject to air compressed by the piston at 40 one end of its stroke, said valve having a fourth pressure area of greater extent than said additional area and the smaller of said differential areas when combined and for overcoming the latter, means admitting motive fluid continuously in limited amount to said fourth area of said valve, means under control of said piston for admitting motive fluid from said piston chamber to said 45 fourth area of said valve, and manually controlled venting means for said fourth area.
- 50 7. In a fluid pressure percussive motor comprising a cylinder providing a piston chamber, a piston reciprocable therein, said cylinder providing an exhaust chamber having a vent to atmosphere substantially centrally of said piston chamber and arranged to be overrun by said piston, an automatically thrown distributing valve moving in timed relation with said piston for controlling the movements of the latter, said cylinder providing an exhaust passage extending to the rear end of said piston chamber and a vent passage 55 extending to a pressure area of said valve, and a manually actuated valve for controlling communication of both said passage and of said exhaust chamber with atmosphere.
- 60 8. In a fluid pressure percussive motor comprising a cylinder providing a piston chamber, a piston reciprocable therein, an automatically thrown distributing valve moving in timed relation with said piston for controlling the movements of the latter, said 65 piston chamber and a main exhaust port controlled by said piston, and a single manually operated valve for controlling said vents and said exhaust port, said last named valve in one position establishing connection of said valve vent and of said main exhaust with atmosphere and in another position cutting off the same and connecting said piston chamber vent to atmosphere.
- 70 9. A fluid pressure percussive motor comprising a cylinder providing a piston chamber, a piston reciprocable therein, said cylinder providing an exhaust chamber having a vent to atmosphere substantially centrally of said piston chamber and arranged to be overrun by said piston, an automatically thrown distributing valve moving in timed relation with said piston for controlling the movements of the latter, said cylinder providing an exhaust passage extending to the rear end of said piston chamber and a vent passage extending to a pressure area of said valve, and a manually actuated valve for controlling communication of both said passage and of said exhaust chamber with atmosphere.
- 75 10. A fluid pressure percussive motor comprising a cylinder providing a piston chamber, a piston reciprocable therein, an automatically thrown distributing valve moving in timed relation with said piston for controlling the movements of the latter, said 80 piston chamber and a main exhaust port controlled by said piston, and a single manually operated valve for controlling said vents and said exhaust port, said last named valve in one position establishing connection of said valve vent and of said main exhaust with atmosphere and in another position cutting off the same and connecting said piston chamber vent to atmosphere.
- 85 11. A fluid pressure percussive motor comprising a cylinder providing a piston chamber, a piston reciprocable therein, said cylinder providing an exhaust chamber having a vent to atmosphere substantially centrally of said piston chamber and arranged to be overrun by said piston, an automatically thrown distributing valve moving in timed relation with said piston for controlling the movements of the latter, said cylinder providing an exhaust passage extending to the rear end of said piston chamber and a vent passage extending to a pressure area of said valve, and a manually actuated valve for controlling communication of both said passage and of said exhaust chamber with atmosphere.
- 90 12. A fluid pressure percussive motor comprising a cylinder providing a piston chamber, a piston reciprocable therein, an automatically thrown distributing valve moving in timed relation with said piston for controlling the movements of the latter, said 95 piston chamber and a main exhaust port controlled by said piston, and a single manually operated valve for controlling said vents and said exhaust port, said last named valve in one position establishing connection of said valve vent and of said main exhaust with atmosphere and in another position cutting off the same and connecting said piston chamber vent to atmosphere.
- 100 13. A fluid pressure percussive motor comprising a cylinder providing a piston chamber, a piston reciprocable therein, said cylinder providing an exhaust chamber having a vent to atmosphere substantially centrally of said piston chamber and arranged to be overrun by said piston, an automatically thrown distributing valve moving in timed relation with said piston for controlling the movements of the latter, said cylinder providing an exhaust passage extending to the rear end of said piston chamber and a vent passage extending to a pressure area of said valve, and a manually actuated valve for controlling communication of both said passage and of said exhaust chamber with atmosphere.
- 105 14. A fluid pressure percussive motor comprising a cylinder providing a piston chamber, a piston reciprocable therein, an automatically thrown distributing valve moving in timed relation with said piston for controlling the movements of the latter, said 110 piston chamber and a main exhaust port controlled by said piston, and a single manually operated valve for controlling said vents and said exhaust port, said last named valve in one position establishing connection of said valve vent and of said main exhaust with atmosphere and in another position cutting off the same and connecting said piston chamber vent to atmosphere.
- 115 15. A fluid pressure percussive motor comprising a cylinder providing a piston chamber, a piston reciprocable therein, said cylinder providing an exhaust chamber having a vent to atmosphere substantially centrally of said piston chamber and arranged to be overrun by said piston, an automatically thrown distributing valve moving in timed relation with said piston for controlling the movements of the latter, said cylinder providing an exhaust passage extending to the rear end of said piston chamber and a vent passage extending to a pressure area of said valve, and a manually actuated valve for controlling communication of both said passage and of said exhaust chamber with atmosphere.
- 120 16. A fluid pressure percussive motor comprising a cylinder providing a piston chamber, a piston reciprocable therein, an automatically thrown distributing valve moving in timed relation with said piston for controlling the movements of the latter, said 125 piston chamber and a main exhaust port controlled by said piston, and a single manually operated valve for controlling said vents and said exhaust port, said last named valve in one position establishing connection of said valve vent and of said main exhaust with atmosphere and in another position cutting off the same and connecting said piston chamber vent to atmosphere.

valve having a pressure area for effecting its movement in one direction, said cylinder providing a vent passage extending to said pressure area of said valve and an exhaust passage extending to the rear end of said piston chamber, and a manually actuated valve for controlling communication of both said passages with atmosphere.

Signed by me at Detroit, in the county of Wayne, and State of Michigan this 13 day of August, 1929.

GUSTAVE M. NELL.
